AUTOMATIC BOILER WATER DECONCENTRATION SYSTEM

Thomas B. Allardice, Mountain Lakes, and
Thomas G. Coghlan, Elizabeth, N. J.Application December 11, 1929
Serial No. 413,178

2 Claims. (Cl. 122—1)

The invention relates to the art of stationary steam boiler operation; and more particularly to the removal of the sludge or sediment present and deposited in a boiler during its operation, as well as to the recovery of a substantial portion of the waste heat involved in such removal.

We are aware that it has heretofore been proposed to periodically blow off and clean steam boilers as by entirely or partly emptying the same, and provision has also been made for partially conserving the thermal units contained in the waste. In contradistinction to such system, the novel system of the present application involves and has for its object a substantially continuous cleaning of, or blow-off of, the sediment or sludge from a stationary steam boiler, with a very high efficiency in conservation of the thermal units involved.

A further object of the invention resides in the arrangement whereby a portion of the water resulting from the blow-off operation is recovered and returned to the boiler, reducing proportionately any hardness of the feed water with which it is subsequently mixed.

To this end, the invention contemplates the more or less continuous removal, as from a mud-drum or from the water level of a boiler, of the sludge and sediment deposited and present therein, said removal being in conformity with the prevailing water level of said boiler, as well as the feed water supply thereto and to which feed water, moreover, the recovered heat is imparted.

In carrying out the invention, the blow-off from the boiler is introduced to a sealed separator container or flash tank wherein the solid matter separates from the vapor, the latter being withdrawn from said tank by means of a jet condenser operated by the boiler feed water. The vapor thus condensed mingles with said feed water and also imparts thereto its thermal units, said feed water then being delivered to a suitable feed water heater or tank and removed therefrom by a boiler pump supplying the preheated feed water to the boiler.

Provision is made, also, to shut off automatically the blow-off operation in the event that the feed water supply resulting from the aforesaid condensation operation exceeds an amount beyond the requirements of the boiler.

As the sediment accumulates in the flash tank, provision is made for periodically discharging the same therefrom, as through an atmospheric seal connected therewith and controlled by a suitable float device. It will be appreciated, therefore, that the aforesaid operation is conducted entirely

automatically and without interfering in any way with the continuous operation of the boiler itself. The nature of the invention, however, will best be understood when described in connection with the accompanying drawing, which sets forth a layout of the novel system and shown more or less diagrammatically.

Referring to the drawing, 10 designates a steam boiler of the stationary type and of any well known or special design provided with the usual mud-drum 11 from which sludge or sediment is to be removed as the same accumulates; or, as is well understood, the matter may be skimmed from the water level in the steam drum, depending on the nature of solids in solution. A blow-off connection 12 is to this end taken from said drum with interposed check valve 13; and a connection 14 with valve 15 is made thereto for manual operation of the blow-off.

In accordance with the invention, however, this is to be effected automatically; and to this end the blow-off connection 12 is continued to a suitably sealed separator container or flash tank 16. The latter is equipped with a discharge pipe 17 of sufficient height, say 36 feet, to effect an atmospheric seal of the tank; and a float 18 of said tank controls through the operation of a valve 19 thereby the discharge of accumulated sludge, etc.

The pipe 17 may dip into and discharge into a drain tank 20 and from which the waste is disposed of in any convenient manner.

Normally, the connection between the drum 11 and tank 16 is open so that said drum will be continuously blown of its solid matter; but in order to obviate discharge under low water level conditions of the boiler 10, a regulator valve 21 of well known or special design is interposed in the connection 12 and when open, as shown, will permit the discharge to take place. However, provision is made to close this valve automatically as by means of a pressure generating member 22 of any well known or special design piped to the boiler drum and operating to vary the control pressure upon valve 21 in manner well understood. The discharge to tank 16 will thus be in conformity with the water level of boiler 10 so that there will be no danger of draining said boiler to a dangerous level.

Tank 16, moreover, communicates with a jet condenser device 25 through the pipe connection 26 in which is interposed a check-valve 27; and the vapor contained in said tank 16 may thus be withdrawn therefrom, the sludge and sediment entering said tank settling in the bottom thereof.

and the separation being assisted by the inter-position of a baffle 28 within the said tank.

It is preferred to have condenser 25 discharge into a feed water heater 30 so as to conserve the 5 water of condensation and recover the heat units thereof, said water also thus reducing in hardness the condensing water employed for the condenser 25 and which is preferably utilized as the feed water for the boiler 10. To this end, the condensing water is introduced through a pipe 31 10 of any suitable source of supply (not shown); and a float 32 in the feed water heater controls a valve 33 of said connection to regulate the water level of said heater.

15 It will be appreciated, however, that if the water for operating the jet condenser 25 is thus shut off or materially reduced by valve 33, it will become necessary to also shut off or reduce the supply of blow-off to tank 16; and to this end a. 20 further regulator valve 35, similar to the valve 21, is included in the line between said valve 21 and the tank 16. When open as indicated, free discharge is had to said tank; but by taking a pressure connection 34 thereto from line 31, a 25 variable pressure effect is had thereon to control said valve 35 in accordance with the action of float valve 33. By this expedient, it will be possible to also shut off automatically or regulate the amount of blow-off from boiler 10 in conformity with the feed water requirements of the 30 boiler, that is to say, the level of the water in feed water tank 30. The water in this tank is delivered in the usual manner to the boiler through a connection 36 from a feed water pump 37 connected with said tank 30 through pipe 38.

The entire action of the boiler blow-off operation is thus automatically accomplished and is in conformity with both the boiler water level and the feed water requirements of the boiler, 40 while discharge of sediment or sludge and the like is substantially continuously effected from the boiler; and the waste water recovered in the separation is returned to the boiler together with

a large proportion of the heat units lost in the blow-off operation.

It will be apparent, of course, that a battery of boilers may be connected to the flash tank 16 as through a header connection 39 between the 80 valves 21 and 35, each boiler in this instance being provided with an automatic shut-off valve similar to the valve 21.

We claim:

1. The combination with a boiler having a blow-off connection and a feed water supply; of a sealed separator container receiving the blow-off from said boiler and provided with a drain, a jet condenser communicating with said separator container to withdraw the vapor therefrom and operated by the feed water prior to its delivery to the boiler, means to regulate the blow-off to the separator container in conformity with the water level of the boiler, and means beyond the first-named blow-off regulating means to regulate the blow-off to the separator container in conformity with the water supply to the jet condenser. 85

2. In combination: a boiler and a blow-off connection therefrom, a valve included in said connection, means automatically regulating the operation of said valve in conformity to the boiler water level; a sealed separator container connected through said valve to the blow-off connection, a jet condenser device communicating with the container for removing vapor therefrom, a feed water connection to the jet condenser for operating the same, a feed water heater tank receiving the heated water from the said jet condenser and a float member in the feed water heater tank, a valve in the feed water connection controlled by said float member, and a further valve in said blow-off connection located between the blow-off connection valve and the separator container and controlled by the pressure in the 115 said feed water connection. 100
